Primary Examiner — Austin Murphy*(74) Attorney, Agent, or Firm* — Loeb & Loeb LLP(57) **CLAIM**

The ornamental design for a soleplate, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of the embodiment of the soleplate showing our new design.

FIG. 2 is a bottom plan view of the soleplate of FIG. 1.

FIG. 3 is a top plan view of the soleplate of FIG. 1.

FIG. 4 is a front elevational view of the soleplate of FIG. 1.

FIG. 5 is a rear elevational view of the soleplate of FIG. 1;

and,

FIG. 6 is a left elevational view of the soleplate of FIG. 1.

A view of the corresponding right side of FIG. 6 has been omitted since the right elevational view is the identical mirror image of the respective left elevational view of FIG. 6. The color appearing in FIGS. 1-6 is known as "champagne" and can be represented by RGB value: 149, 144, 119 or Pantone Solid Uncoated 451 U.
